GUIDO ALFANI, OF FIRENZE, AND LEANDRO MAZZA, OF GENOA, ITALY.

SELECTOR FOR AUTOMATIC TELEPHONE EXCHANGES.

Application filed March 31, 1922, Serial No. 548,389, and in Italy April 1, 1921.

The present invention refers to improvements in and relates to automatic switch board systems or selectors for electric circuits and particularly for telephone circuits such, for example, as those employed in automatic telephone exchanges in similar installations and its principal object is to provide these selectors (which are adapted particularly for use either as group-selectors or 10 connectors) of compact and simple construction, of sure working and low cost of establishment.

Each selector consists essentially, as in systems hitherto known, of three parts, that 15 is to say, a certain number of fixed contacts which form the so-called bank of contacts, these fixed contacts corresponding generally to 100 lines connected to the telephone exchange and sometimes to a larger or smaller 20 number; and one or more movable contacts mounted upon a mechanism which may be termed the movable equipment, the said contacts being connected, independently of the operation proper of the selector, to the line 25 of the calling station; and finally the motor elements.

It should be pointed out here that the principle of multiple utilization is applied with a law of simultaneous action to the 30 bank of contacts, while it is applied with a law of successive action to the movable equipment and above all to the motor elements which control it. To this end the contacts in the bank are so formed as to effect 35 simultaneously the connection between the contacts and the bank of one and the same selector, and to serve for the multiplication between the corresponding contacts of the banks of several selectors. On the other 40 hand, all the movements of the movable equipment, by varying successively the functions performed respectively by the elements composing it, are controlled by a single motor, which by means of suitable mechanism 45 acts in a different manner upon the movable equipment according to the various phases of operation in which the selector happens to be.

According to the present invention the 50 fixed contacts are in the form of flat bars or the like, and the bank of contacts is so formed that the individual contacts of each series are arranged parallel one to the other, in the same plane, which plane is parallel 55 to other planes in which are arranged analog-

ously and homologously the individual contacts of the other series. These flat bars extend uninterruptedly beyond the bank element to which they belong, so as to constitute a series of banks of contacts, each 60 constituting a complete unit, that is to say, a multiple bank of contacts serving a number of selectors, without the use of multiplying cables.

The foregoing is a very important characteristic of the present system of selectors, upon which depends its great simplicity and certainty of operation as compared with other systems of selectors hitherto known. In these systems the banks of contacts are 70 formed in metallic blocks arranged radially in a certain number of planes between semicircular sectors of insulating material. The group of sectors and contacts is bolted together so as to form a block and the contacts 75 extend into the interior of the block to form the fixed contacts proper and extend externally for the attachment of the wires of the multiplying cables which in this case are 80 necessary.

According to the present invention the movable equipment—controlled by the action of one electromotor having interrupted or step by step movement, (or one having continuous movement),—causes the movable 85 contacts to move, and they establish the desired connection with the fixed contacts of the bank, moving first in one direction to pick out one of the several series of fixed contacts and then in another direction to 90 pick out the individual contact in the series. These movable contacts are mounted so as to move successively in two directions at right angles to one another. In some simplified constructions, however, and in particular in 95 those constructions of selector in which the fixed contacts are limited in number, the movable contacts are adapted to move in one direction only.

The principle of multiple utilization successively is applied by means of a special device which may be termed an electromechanical combiner and not only provides in known manner for successively changing the 100 internal circuits of the selector necessary for controlling it during the different phases of its operation, but it also accomplishes in a manner absolutely novel various operations 105 which are entirely mechanical. They may, for example, consist in modifying the me- 110

chanical connections existing between the different elements, so that the movable equipment may cause the contacts to move successively in two directions, although there is only one electromagnet motor; or in effecting the release of the movable equipment so that it may return to the point of departure; or in other analogous operations such as connecting the armature of the electromagnet motor with the shaft for rotating the combiner so as to move it, without an additional motor being required, from one position to another according to the phase of operation of the selector.

What has been said above represents another of the characteristics which makes the present system of selectors essentially different from selectors hitherto known and increases the already great simplicity and certainty of its operation, due to the above described special form of multiple bank. It will be seen that in this arrangement a single electromagnet takes the place of four or five electromagnets, that is to say, the electromagnet motor provides in the case directly or indirectly for the two movements of the movable equipment, for its release, and it may also provide for the control of the combiner, whereas in other systems two separate electromagnets are provided for the movements of the movable equipment, a third electromagnet for its release, a fourth for the control of the device which corresponds to the present combiner and finally a fifth electromagnet for effecting the disconnection required when the said device returns to the position of rest by a return movement.

In the accompanying drawings Fig. 1 shows a perspective view of a multiple bank of fixed contacts with corresponding movable contacts, and Fig. 2 is a transverse section on a smaller scale of two modifications; Fig. 3 is an assembled view of a selector with two movements, and Figs. 4 to 8 illustrate special constructions and corresponding modifications; Fig. 9 shows a selector with one movement, and Fig. 10 a modification thereof.

In Fig. 1 there is shown at the upper part (which is only the upper part in the drawing) a portion of a multiple bank comprising, at the right hand side, the head of the bank (the same term may be applied to the other end also), at the centre two complete bank elements relating to two commutators and at the left-hand side a portion of a third bank element.

The multiple bank illustrated serves for two-pole lines (it will be evident that in this case the commutators served thereby are also two-pole) with separate groups for each pole, that is to say, there are two groups, each of which by itself may constitute a one-pole bank. In the first group are assembled

all the contacts *a* which may be the outward contacts, and in the second group are assembled all the contacts *b* which may be the return contacts. Each line is therefore made up, in the case of a two-pole bank, of a contact *a* and a contact *b* and in particular, there correspond to each line 1, 2, . . . *x*, the contacts *a*¹ *b*¹, *a*² *b*² . . . *a*^{*x*} *b*^{*x*}. All these contacts, as has been stated and as can be seen from the drawing, are in the form of flat bars, but may be of any other suitable shape.

For the sake of simplicity in the drawing the bank of contacts is shown corresponding only to 25 two-pole lines, divided into five series, each of five lines, carrying in all 50 contacts in the form of flat bars. All these bars are parallel to one another and are arranged at equal distances from one another, in a number of planes. The bars of the same series of lines are arranged in two of these planes, one plane in each group of the bank: for example, the individual bars *a* of the first series (lines 1; 2, 3, 4, and 5), that is to say, the bars *a*¹, *a*², *a*³, *a*⁴, and *a*⁵, are arranged at equal distances from one another in the first plane in each group; while all the individual bars *b*¹, *b*², *b*³, *b*⁴, and *b*⁵, of the same first series are arranged at the same distance from one another in the first plane in the other group; and analogously are arranged the other bars *a* and *b* of the other four series of lines.

All the five planes of bars *a* in one group are parallel to and equidistant from one another and are usually placed at the same distance from one another as the several bars in each plane; and analogously the five planes of bars *b* in the other group are parallel to one another and equidistant, and the bars in those planes are at equal distances apart; the distance between the last plane *a* and the first plane *b* may, however, be different, as may be found convenient. Moreover all the bars *a* and *b* belonging to lines of the same order in each series, for example, the bars *a*¹, *a*⁶, *a*¹¹, *a*¹⁶, and *a*²¹, *b*¹, *b*⁶, *b*¹¹, *b*¹⁶, and *b*²¹, and so on, are arranged in planes perpendicular to the planes of the series of lines.

In order that the fixed contacts in the form of flattened bars may rigidly retain their respective positions and be effectively insulated from one another, they are fixed in supporting plates 26, 26', 26'' etc. of suitable form and composition, arranged at regular intervals transversely to the said bar contacts. The front of the plate 26 constitutes the head of the multiple bank and all the bars project a short distance beyond it and form small fingers of a suitable shape, to receive the soldered multiplying wires. The plates 26 and 26' form the limits of the first bank element which corresponds to the first commutator, the plates 26' and 26'' form the limits of the second bank element and be-

yond the plate 26" can be seen the third bank element. The number of bank elements which go to form a multiple bank depends upon the space available upon the frame work upon which the commutators are mounted and above all upon the number of auxiliary lines for which the telephone exchange has to provide.

Below the first two bank elements is clearly seen part of the movable equipment of the first two commutators, that is to say, the switch contacts 27 with their mounting. Each contact is formed of two similar springs 28, one opposite the other but electrically connected. At their lower ends the said springs are fixed in blocks 29 rigid with the switch contact carrier 30 which is partially visible. The springs are situated in planes parallel to the planes of the bars in the bank of contacts and so fixed as to engage the said bars perpendicularly or at a suitable angle of incidence and to embrace them and to press against their side surfaces. At the upper ends the springs are shaped so as to wipe or rub easily upon the side surfaces of the bars and to ensure a good electric contact with them; moreover the rubbing extremities should be shaped so as to pass from one bar to the next without causing a short circuit between the bars. The springs are covered by suitable sheaths of insulating material 31, covering them on the inside and outside for their whole length, except for the rubbing extremities, so as to prevent, undesired contact between the said springs and any one of the bars over which the rubbing extremities have passed.

In view of the parallelopiped form of the multiple bank it is clear that the movement suited to allow the contact brushes to select first of all the series of lines and then the individual line in that series, is as already indicated, namely rectilinear movement in a plane at right angles to the bars in the bank. Moreover as clearly shown by the drawing which indicates the switch contacts of the first and second selectors respectively in the position of engagement with line 3 and in the position of rest, the said movement is first of all perpendicular to the planes of the bars and in a direction towards the right hand and then perpendicular to the said bars in an upward direction.

The bank of contacts with one-pole groups as described above with brush contacts is the most simple and generally employed form, because it lends itself readily without any change to the case of commutators having any number of poles. By arranging one beside another, two, three, four or more one-pole groups there are obtained respectively two-pole (like that above described), three-pole, four-pole banks of contacts, and so on.

It is, however, clear that in the case of a two-pole bank it need not necessarily be di-

vided into two one-pole groups but the planes of contact bars may be arranged in a single two-pole group. To this end it is sufficient to follow the plane of individual bars *a* of one series (for example that of the bars *a*¹, *a*², *a*³, *a*⁴, and *a*⁵—with the plane of individual bars *b* of the same series (for example bars *b*¹, *b*², *b*³, *b*⁴, and *b*⁵). This arrangement may be carried out in two ways, either by coupling the two planes *a* and *b* of the same series or by coupling the planes *b* of one series with the planes *a* of the succeeding series.

Fig. 2 shows in transverse section and on a reduced scale a four-pole bank (again with 25 lines for the sake of simplicity) divided into two two-pole groups. In the first two-pole group the planes of bars are arranged according to the first method and in the other group they are arranged according to the second method, but this is done purely for the purpose of demonstration. The switch contacts 32 of the first group are identical with those above described, with the exception of their two springs, which are insulated electrically from one another and are slightly further apart, so as to embrace instead of a single bar, a pair of bars, for example, *ab*, *a'b'*, *a''b''* etc. On the other hand the switch contacts 33 for the second group are slightly different; being intended here to be inserted between the two bars of each pair instead of to embrace the pair; the rubbing extremities of the springs are suitably modified, as are also the insulating sheaths that surround them. It is evident that the multi-polar banks, instead of being formed of several one-pole groups corresponding to the number of poles, may also be obtained by uniting several two-pole groups such as those above described with the addition in some cases of a single one-pole group. It is moreover clear that in the case of banks formed by a single series of lines (such as will be used with the simplest form of commutator) the division of the bank into one-pole groups has almost identically the same result as the division into two-pole groups.

Figure 3 shows an assembled view of a commutator with two movements, comprising a bank of fixed contacts, a movable equipment, motor elements and an electro-mechanical combiner. The said combiner, upon which depends particularly the operation of the whole apparatus, can be seen at the left of the figure; and it comprises (see also Fig. 6) a shaft 34, carrying a certain number of discs 35, 36, 37, 38 . . . etc. the edges of which are provided with a cam profile which may be disposed either radially (as in the figures) or axially in the direction of the shaft, that is to say on a crown mounted on the edge of said discs. It should be pointed out that in place of a

simple profile it is possible to employ in every case a channel or slot. The levers 39, 40, 41 ... etc. of suitable kind and shape are caused by suitable means to slide with one of their ends upon the profile of the discs and are moved by these profiles and may assume two, three or more different positions and control consequently by means of the other ends the draw rods 42, 43, 44 etc. carried and guided by suitable supports 45, fixed to the frame 46 of the commutator. These controlled movements are then transmitted by the draw rods to the several mechanisms which compose the movable equipment and the motor elements and modify their connection with one another. Some of these said mechanisms may be controlled (through the said draw rods and in particular the draw rod 42) by the change-over electromagnet 47, or rather by its armature 48, every time that it is necessary to change over from the movement of the movable equipment to the movement of the combiner. The change-over electromagnet forms an integral part of the said combiner.

The use of a special device, such as the said combiner to produce the successive mechanical changes described according to the necessities of the various phases of operation is particularly adapted to automatic telephone exchanges.

In addition to the said purely mechanical operations, the combiner provides in known manner for analogous successive changes of an electric nature. In the figure it will be seen that corresponding to the position of the disc 38, the spring contact 49 is pressed by the profile of the disc into three definite positions, either against the fixed contact 49' so as to close one circuit, or against the fixed contact 49'' so as to close another circuit, or finally in the midway position between the two contacts so that both circuits remain open, as shown in the drawing. Similar spring contacts, that is to say, the end contacts 50 and the lateral contacts 51 may be operated in known manner by the movable equipment on starting its first and second movements respectively.

The shaft 34 of the combiner turns in a counter clockwise direction when viewed from its lower extremity and with it turn the discs, the whole being rotated by the ratchet wheel 52, which is controlled by a pawl 84. The shaft and consequently the whole of the combiner can only come to rest in definite positions which are conveniently fixed at the same angular distance from one another.

In each of the said positions the combiner accomplishes according to the profiles of the discs a certain number of mechanical connections and a certain number of openings and closings of electric circuits; it may moreover perform analogous operations in

the intermediate position of transit, that is to say, in the positions through which the combiner passes, without stopping, during the rotation of the shaft. The order in which these operations follow will clearly be invariable and predetermined.

The number of the positions of the combiner, the number of the discs and their profile, and also the kind and shape of levers employed may vary, according to the electromechanical combinations that are required for each particular model of commutator, to the particular use to which it is to be put and to the particular internal circuits. In the figures under consideration however, the combiner has six possible positions.

In the upper part of Figure 3 is seen the bank of contacts in section on a plane perpendicular to the bars, so that one of the plates 26 in which the bars are fixed is seen. The plates and by their means the bank of contacts are suitably mounted on the frame 46.

In the centre of the figure is seen the movable equipment comprising the brush carriage 30 with its switch contacts 27, and two shafts 53 and 54 which may be termed respectively the controlling shaft and the controlled shaft. These shafts are parallel with one another and at right angles to the planes of bars and they lie in a plane at right angles to the bars. They are held and guided by special supports mounted upon the frame so that they can move freely towards the left in the direction of their axis and return to the starting point, their return movement being limited by the flanges or collars 55, and 56. The said shafts cannot, however, turn about their axes.

The double translatory movement of the brush carriage and consequently of the switch contacts is produced by a single movement of the controlling shaft which is effected in two phases. In the first phase the controlled shaft is locked to the controlling shaft and both move together; and in the second phase on the other hand the controlled shaft is locked to the frame and only the controlling shaft moves. The arrangement is such that the controlled shaft is at all times locked to one or the other and is never independent. This result is effected by means of the combiner which controls suitable engaging means.

The controlling shaft has near one end (at the left in the figure) a slot 57 and a rack provided with ratchet teeth 58, which are placed at the same distance apart as the planes of contact bars and in number are equal, to the number of series of lines plus the number of lines in a series, that is to say, they are equal in number to the sum of the double translatory movement; in the case under

consideration there are 10 teeth. The controlled shaft, on the other hand, has near its corresponding end (at the left in the figure) slots 59 which are also arranged at a 5 distance from one another corresponding to the teeth of the racks 58, but are fewer in number and in fact equal in number the series of lines, in the present case, five. The said controlled shaft carries, moreover, on 10 this end a sleeve 60 which can turn about the shaft but which cannot slide along the shaft.

The engagement mechanism just mentioned consists essentially of this sleeve and 15 of the elements working with it or of similar devices taking their origin from it. Upon the sleeve are mounted at right angles to the shaft two arms (compare the details in Fig. 4) the first of which 61 is formed like 20 a blade and can enter the slot 57 in the controlling shaft thus locking it firmly to the controlled shaft; whilst the other arm 62 is in the form of a fork. This fork engages a rod 63 which is fixed parallel to the controlled shaft upon a lateral extension 64 of 25 the draw rod 44; and this rod is of such length that it always remains engaged by the fork even when the controlled shaft travels its full course.

30 The draw rod 44 enters with its end 65, which is suitably shaped, the slots 59 so as to lock the controlled shaft to the frame whenever the lever 41 acts by means of the pin 66 upon the draw rod 44. When this 35 action ceases the draw rod returns to its ordinary position and releases the controlled shaft which is drawn back by a suitable opposing force. It is evident that in view of the relations between the rod 63 and the fork 40 62, this return can only take place when the blade 61 registers with the slot 57 and can freely enter it. There is thus realized the condition that the controlled shaft is always locked either to the controlling shaft or to 45 the frame of the commutator; it must be pointed out moreover that the connection with the controlling shaft can only take place when the two shafts are in a particular position with respect to one another, 50 whilst the other connection can take place in as many positions as there are slots 59.

55 The switch contact carriage 30 is mounted upon the controlled shaft and it is guided by a guide frame 67 which is carried by the controlled shaft or by similar means so that the carriage possesses independently of the controlled shaft a single freedom of movement perpendicular to the two shafts and at the same time perpendicular to the contact 60 bars.

65 This independent movement of the carriage is produced by the movement of the controlling shaft during the second phase, that is to say, by its movement relatively to the controlled shaft, which during the sec-

ond phase remains stationary; it is as has been said perpendicular to the movement effected by the brush carriage with the controlled shaft and the controlling shaft during the first phase, and may be obtained by 70 various means which generally speaking are based upon the means to be described below.

A pinion 68 of suitable length has its axis journalled at 69, in the frame 67 parallel to the contact bars. The pinion engages 75 with two racks 70 and 71 perpendicular to one another and parallel respectively to the two movements of the switch contact carriage. The said racks are fixed as is natural in parallel planes, the first of them upon 80 the controlling shaft and the other upon the carriage. It is now clear that when the controlling shaft takes the controlled shaft in its movement towards the left, the carriage follows the said movement without making 85 any movement of its own and moves the switch contacts to the point for selecting the series of lines required; while when only the controlling shaft moves to the left and the controlled shaft is stationary, the rack 70 90 causes the pinion to turn in a clockwise direction and the pinion in turn by means of the rack 71 causes the carriage to rise, so that the switch contacts establish contact 95 with the individual line in the series chosen.

Finally the lower part of Fig. 3 shows the motor elements, that is to say the step magnet 72 with its armature 73 and the various mechanisms which receive their movements from it. It should be here noted that the successive utilization which has been mentioned of a single electromagnet for giving the necessary movements to the elements composing the movable equipment and also for moving the combiner, can be 100 done with the aid of the combiner, substantially in two ways; either by bringing the several mechanisms which are to be moved or instead of bringing the mechanisms, bringing special elements connected therewith successively into engagement with the step magnet armature; or by bringing the 105 said armature or rather a movable element connected therewith successively into engagement with the said mechanisms. The first 110 way most satisfactorily meets the operative requirements because it makes possible, while confining each instant the movement to the individual parts necessary, for the employment of a simple armature, that is to say one 115 without movable connections or other accessories and it is consequently better adapted with an electromagnet of equal power to answer to rapid impulses.

In accordance with the first way the end 125 73' of the step magnet armature is suitably shaped and transmits directly its movement to the rods 74 and 75, which in turn are put into engagement with it by the draw rod 42, which moves them by means of the pins 130

76 and 77. The two rods 74 and 75 are pivoted at 78 and 79 respectively upon supports 80 and 81 which turn about pivots 82 and 83. They transmit the movement received 5 from the armature 73 respectively to the ratchet wheel 52 and consequently to the shaft of the combiner, to the rack 58, and consequently to the controlling shaft, by means of pawls 84 and 85. The draw rod 10 42 is operated so as to present the rod 74 and consequently to make ready for the movement of the combiner, either by means of the lever 39 (as shown in the drawing) or by the change-over magnet 47. On the 15 other hand, the rod 42 is actuated so as to present the rod 75 and consequently to make ready for the movement of the controlling shaft by means of any suitable opposing force, which can act, it will be understood, 20 when neither the lever 39 nor the armature 48 is acting.

A retaining pawl 86 pivoted at 87 holds the controlling shaft by means of the racks 58 in the successive positions reached. The 25 said pawl is caused by the draw rod 43 to disengage itself from the rack (as shown in the drawing); and it is on the other hand caused to engage in the rack by means of a suitable opposing force.

30 According, however, to the second way of transmitting the movement (see, Figure 5) the armature 73 controls the rods 74 and 75 by means of a finger 88 pivoted at 89 upon the said armature which finger controls, in 35 turn that one of the two rods to which it is presented by the draw rod 42 of the combiner between the pins 76 and 77 of which it is carried. The draw rod 42 acts in this case upon the finger 88 instead of upon the 40 rods 74 and 75.

It is easy to follow the operation of the commutator, in a simple example, in one of the cases where it is most frequently used, in the case that is to say where it performs 45 the operation of a selector in an automatic telephone exchange.

When the commutator enters into operation, the step magnet receives a current impulse and attracts the armature which by 50 means of the rod 74 and corresponding pawl causes the combiner to move from position I to position II. In this position the levers 39 and 40 release their corresponding draw rods; and the rod 75 is brought into engagement 55 with the armature 73 whereby the pawl 86 engages with the rack 58. Current impulses from the calling station then arrive, directly or retransmitted by relays, to the step magnet which attracts its armature as 60 often as it receives these impulses and since the armature operates the rod 75 and its corresponding pawl, the controlling shaft and with it all the movable equipment moves towards the left a corresponding number of 65 steps. If the calling station as we may sup-

pose has sent only a single impulse, the controlling shaft moves a single step, remaining held in this position by the pawl 86 and the switch contacts are moved into a position opposite the bars of the first series of lines. 70 Immediately afterwards by the combined action of the head contacts 50 as operated by the first movement of the movable equipment, of the cessation of impulses from the calling station and of various relays which are not indicated in the drawing and the operation of which does not concern the present specification, the change-over magnet 47 is excited and attracts its armature so as to again make the step magnet ready to operate the 75 combiner and this takes place immediately a new current impulse reaches the said step magnet motor.

In the position III of the combiner the magnet 47 is de-energized to allow the lever 85 75 to return to a position opposite the armature 73, the draw rod 44 pressed by the lever 41 enters with its end 65 into the slot 59, which is opposite it (in the present case the first tooth), and at the same time causes the 80 blade 61 to leave the slot 57. Since the controlled shaft is thus locked to the frame 46, and only the controlling shaft is free to move, the second current impulses from the 85 calling station are transformed into a further displacement of the controlling shaft towards the left and consequently into a vertical upward displacement of the carriage and switch contacts. If for example three new impulses arrive from the calling station 90 the controlling shaft moves three more steps, coming to rest after having moved four steps in all, and the switch contacts are moved so as to establish contact with line 3, as indicated in Fig. 1, that is to say with the bars 95 a^3 and b^3 . The whole movable equipment then remains in this position held by the pawl 86. Immediately afterwards, and again by the combined action above described, to which may be added in this case the commutation of the lateral contacts 51 caused by the first independent movement of the carriage the change-over magnet 47 is again excited and the step magnet is again prepared to operate the combiner and immediately a new current impulse reaches the 100 step magnet, the combiner etc., passes to position IV in which the lever 39 brings the draw rod 42 again into the position shown in the figure.

The position under consideration and the following positions, IV, V and VI may serve for other necessary operations such for example as testing the station called, the transmission of the signal "busy" to the calling station, if the station called is busy, the transmission of the calling signal to the station called, if it is free, the operation of the meter and finally the conversation. All 105 these operations are carried out independ- 110 115 120 125 130

ently of the true and proper movement of the commutator by the combined action, more particularly of various relays and electric connections effected by the combiner, and relating to the particular internal circuits of the commutator and to the particular type of telephone exchange but not relating to the present invention.

When the conversation is ended which we 10 may suppose takes place when the combiner is in position VI, the current impulse traversing the step magnet brings back the combiner into the position of rest, that is to say, into position I, in which the draw rod 43 causes the retaining pawl 86 to disengage 15 from the rack 58. In this manner the controlling shaft under the action of a suitable opposing force travels back until its collar 55 strikes against the blade 61, and at the same time the brush carriage under similar 20 action sinks again upon the controlled shaft; it is only at this moment, since in the position I of the combiner the action of the lever 41 upon the draw rod 44 ceases, that the blade 25 61 can enter the slot 57 opposite which it finds itself and the return movement of the controlling shaft can continue, taking with it the controlled shaft until they have both regained their starting position, that is to say, until the flange or collar 56 strikes against the frame.

The second movement of the brush carriage, that is to say the independent movement may be obtained as has been said in a 35 variety of ways other than that above described. In particular there may be employed instead of the pinion 68 simultaneously engaging with the two racks 70 and 71, two toothed wheels or two toothed sectors, 40 fixed upon the same axis 69, each engaging with one of the racks. It should be noted that if the wheels or the sectors are of different diameters the advance movements made by the controlling shaft will be different 45 from those made by the carriage.

Finally there may be used instead of wheels and sectors, a lever bent at right angles, pivoted about the axis 69. The two racks 70 and 71 are replaced by two pivot pins arranged so that when only the controlling shaft moves the first pivot which is fixed to the said controlling shaft pushes one arm of the bent lever while the second pivot fixed to the brush carriage is moved by the other 55 arm of the lever so that the carriage with the second pivot is moved vertically. It should also be noted that if the arms of the lever are unequal the movements of the controlling shaft and of the carriage will be of different extent.

It is also possible to use, instead of a bent lever, eccentrics or an inclined plane mounted upon the controlling shaft or upon the carriage, or to employ suitable combinations of 60 the elements mentioned or any other suitable

element. Finally it is also possible to arrange the two shafts, both the controlling and the controlled shaft, in a plane parallel to the contact bars instead of in a plane perpendicular to the said bars, or even in another plane, or one of the shafts may be made hollow and the other shaft arranged within it.

In the principal construction of the movable equipment which we have described and 75 in its modifications, the contact brushes are always moved by a double translatory movement. We have even noted that the said movement is that which is most suitable, given the characteristic form of the bank of 80 contacts. This assumption being made it may be pointed out that the second movement in particular of the switch contacts, the movement for the selection of the individual line in the series may, while retaining sufficient simplicity in the elements be a rotary movement. In this case the whole of the movable equipment takes a form analogous to that of other systems of selectors already known.

Figure 6 represents in a transverse section of the bank of contacts, the assembly of a commutator having two movements, provided with a movable equipment with rotating switch contacts or brushes. The combiner and the bank of contacts can be seen respectively at the top on the left hand side and at the right, and the movable equipment is in the centre of the figure. The movable equipment comprises simply the shaft 90, on 100 which are directly mounted by means of pincers 29 the contact brushes 27. The shaft is arranged perpendicular to the planes of the contact bars being held and guided by special supports mounted on the frame 46, 105 so that it is free to travel easily towards the left in the direction of its axis and to return to the starting point, its return movement being limited by the flange or collar 91, and also being free to turn in both directions.

The contact brushes are formed of springs 110 identical in form and arrangement with those already described except for the fact that as is convenient in this case they meet the first bars during their movement at a 115 smaller angle; and this can easily be seen from Fig. 7 which shows a part of the commutator in longitudinal section.

The double movement of the carriage and the consequent movement of the brushes is 120 here replaced by the double movement first of displacement towards the left and then the rotary movement in clockwise direction, looking at the left hand end of the shaft; and in the first movement as will be seen the 125 brushes are brought to a position to select the series of lines required, whilst in the second they are caused to establish contact with the individual line in the series selected.

In order to receive these two movements 130

from the step magnet, the shaft bears on one of its ends, the left hand end in the figure, two racks 92 and 93; the first is provided with annular ratchet teeth at a distance from 5 one another equal to the distance apart of the planes of contact bars and in number equal to the number of series of lines (in the present case five teeth), whilst the other rack is in the form of longitudinal grooves or ratchet teeth 10 in number equal to the number of lines in a series (in the present instance five). The distance between the longitudinal teeth gradually increases proportionately with the angle through which the brushes must turn in 15 order to reach the bars. Assuming that the bars are equal distances apart, the angular movement of the shaft increases during the passage of the brushes from one bar to the next. Nevertheless if a decreasing distance 20 were chosen between the bars the angular movement of the shaft could remain constant.

At the lower part of the figure are seen the motor elements of the commutator which 25 are entirely identical with the elements already described. However, between the rods 74 and 75 there is here a third rod 94 which by means of a bent lever 95 pivoted at 96 and of the pawl 97, transmits a rotary movement to the shaft. There is also a second retaining pawl 98 pivoted at 99 and controlled by the finger 86 of the pawl 86 and consequently by the draw rod 43, which retains, with the aid of the longitudinal rack, 30 the shaft in the successive positions which it reaches in its rotation. However in this case it will be understood the control rod 42 may act, instead of upon the rods 74, 75 and 35 94, upon a finger of the step magnet armature in the same way as was indicated in Figure 5.

The operation of the said commutator with rotating brushes as a connector is effected in the manner already described except for slight differences. In the position 45 III of the combiner, since the draw rod 42 presents the rod 94 to the step magnet armature, there is obtained a rotary movement of the shaft when the second current impulses 50 arrive from the calling station. Finally when the conversation is finished and the combiner returns to position I the draw rod 43 causes the pawls 86 and 98 to disengage from their respective racks and the shaft, 55 under the action of suitable opposing forces, first of all rotates in the opposite direction until the contact brushes are free of the bars and then returns to its position of rest.

It is important to note how it is possible 60 to combine the principal construction of the movable equipment with the equipment of rotating brushes described above. It is in fact possible to give the brushes the double movement as in the principal construction 65 by making use of a shaft having a move-

ment of displacement and a movement of rotation. Figure 8 shows by way of example a method of carrying out this combined construction according to which on the shaft 90 there are fixed, instead of 70 brushes, two similar projecting fingers 100 between which is arranged a pinion 101, engaging with the rack 102 of the carriage 30. The said projecting fingers serve to set the carriage in movement sliding along a shaft 75 103 fixed to the frame 46. This shaft only serves the purpose of guiding the carriage, when during the rotation of the shaft 90 it is obliged to move in an upward direction. The said guiding element can often be arranged directly between the carriage and the frame or in any other equivalent manner. In the same way as has been above described with regard to the principal construction of the movable equipment, and here also it is possible to employ instead of 80 the elements described other kinematic elements suitably combined and performing equivalent functions.

Figure 9 illustrates a construction of a 90 simplified commutator provided with a single direction of movement. Above it is seen the bank of contacts which by way of example is formed of a single series of 5 two-pole lines, that is to say, having only 10 contacts in the form of flat bars. Below is the movable equipment comprising the shaft 104 and the brush carriage 30. The shaft receives its motive impulse through the rack 105 and transmits it by means of the other 95 rack 70 to the pinion 68 which in turn transmits it to the third rack 71 so that the carriage is obliged to move upwards. The shaft 106 is fixed upon the frame 46 and only serves to carry the guide frame 67. 100 Even in this simplified form of commutator it is possible to employ an equipment with rotating brushes, (similar to that shown in Fig. 6) or a combined equipment (similar to that shown in Fig. 8); and it is moreover 110 possible to replace the pinion by means of any of the arrangements discussed.

Finally it is possible to attain a still greater degree of simplicity, (compare Fig. 10), by reuniting the shaft 104 and the carriage 30 into a single organ. In this case the movable equipment is reduced to the carriage alone, which, suitably guided by the frame 67, carries directly the rack 107 by means of which it receives the movement 120 which is given to it by the magnet.

We claim as our invention:

1. A selector system for automatic telephone exchanges, comprising a frame; insulating supporting plates secured to said frame; a plurality of parallel flat bars arranged transversely to and in said supporting plates to form a succession of banks, said banks being divided into separated one-pole groups; a controlling shaft mount 130

- ed in said frame; a controlled shaft mounted in said frame, said shafts being parallel to one another and perpendicular to the planes of the bars and arranged in a same plane perpendicular to the bars; a switch contact carrier having separate switch elements for each group of the bank mounted in said controlled shaft and adapted to contact with said bars; means for actuating both said shafts to move said switch carrier laterally under said bars; and means for actuating said controlling shaft laterally, said controlled shaft remaining stationary for moving said carrier longitudinally in order that the switch elements may contact with said bars.
2. A selector system for automatic telephone exchanges comprising a frame; insulating supporting plates secured to said frame; a plurality of parallel flat bars arranged transversely to and in said supporting plates to form a succession of banks, said banks being divided into separate one-pole groups; a controlling shaft mounted in said frame; a controlled shaft mounted in said frame, said shafts being parallel to one another and perpendicular to the planes of the bars and arranged in a same plane perpendicular to the bars; a switch contact carrier having separate switch elements for each group of the bank mounted in said controlled shaft and adapted to contact with said bars; a combiner associated with said parallel shafts; an electromagnet for operating both said shafts laterally to operate said switch carrier laterally; and means controlled by said combiner for operating said controlling shaft laterally, said controlled shaft remaining stationary, to move said carrier longitudinally so that said switch elements will contact with said bars.
3. A selector system for automatic telephone exchanges comprising a frame having a plurality of flat parallel bars mounted therein by means of insulating supporting plates; actuating means mounted in said frame; a switch contact carrier having switch elements mounted in said actuating means; a combiner comprising a shaft and a plurality of discs; a plurality of levers associated with said discs; and means for rotating said shaft and discs to actuate said actuating means in order that said switch elements may contact with said bars.
4. A selector system for automatic telephone exchanges comprising a frame; insulating supporting plates secured to said frame; a plurality of parallel flat bars arranged transversely to and in said supporting plates to form a succession of banks, said banks being divided into separate one-pole groups; a controlling shaft mounted in said frame; a controlled shaft mounted in said frame, said shafts being parallel to one another and perpendicular to the planes of the bars and arranged in a same plane perpendicular to the bars; a switch contact carrier having separate switch elements for each group of the bank mounted in said controlled shaft and adapted to contact with said bars; means for actuating both said shafts to move said switch carrier laterally under said bars; and means for moving said carrier longitudinally, one of said shafts remaining stationary so that the switch elements may contact with said bars.
5. A selector system for automatic telephone exchanges comprising a frame; insulating supporting plates secured to said frame; a plurality of flat parallel bars arranged transversely to and in said supporting plates; a controlled shaft mounted in said frame; a controlling shaft mounted in said frame having ratchet teeth at one end; means for connecting said shafts together; a combiner comprising a shaft and a plurality of discs; a plurality of levers associated with said discs; a switch contact carrier having switch elements mounted on said controlled shaft; means associated with said ratchet teeth for moving said shafts laterally to move said switch carrier laterally; and means associated with said ratchet teeth for moving said controlling shaft laterally to move said switch carrier longitudinally so that said switch elements may contact with said bars.
6. A selector system for automatic telephone exchanges comprising a frame; insulating supporting plates secured to said frame; a plurality of parallel flat bars arranged transversely to and in said supporting plates to form a succession of banks, said banks being divided into separate one-pole groups; a switch contact carrier having switch elements thereon for each group of the bank and adapted to contact with said bars; a pair of parallel shafts mounted in said frame, said switch carrier being mounted in one of said shafts; a combiner associated with said shafts; means for connecting said shafts and said combiner together; means for operating both said shafts to move said switch carrier laterally under said bars; and means for moving said carrier longitudinally, one of said shafts remaining stationary so that the switch elements may contact with said bars.
7. A selector system for automatic telephone exchanges comprising a frame; insulating supporting plates secured to said frame; a plurality of flat parallel bars mounted in said supporting plates; a combiner associated with said frame comprising a plurality of discs; controlled and controlling shafts mounted in said frame; a plurality of levers operated by said discs; a step magnet for operating said combiner and

said controlling shaft; a change-over magnet for controlling the actuation of said combiner and said controlling shaft; means for moving said shafts simultaneously upon actuation of said step magnet to move said switch carrier laterally under said bars; and means for moving said switch carrier longi-

tudinally in order that the contact elements may contact with said bars.

In testimony whereof we affix our signatures.
